UNITED STATES PATENT OFFICE.

HARRY BLOUNT, OF OAK PARK, ILLINOIS, ASSIGNOR TO WESTERN ELECTRIC COMPANY, INCORPORATED, OF NEW YORK, N. Y., A CORPORATION OF NEW YORK.

WIREDRAWING DIE.

Application filed May 12, 1920. Serial No. 380,825.

To all whom it may concern:

Be it known that I, HARRY BLOUNT, a citizen of the United States, residing at Oak Park, in the county of Cook and State 5 of Illinois, have invented certain new and useful Improvements in Wiredrawing Dies, of which the following is a full, clear, concise, and exact description.

This invention relates to wire drawing 10 dies, and has for its object to produce a form of die for wire drawing operations which will permit the drawing of wire therethrough at high speed without breakage of the wire and which will be efficient 15 and accurate and will have a long life.

Investigation of former wire drawing machines has disclosed that they are necessarily limited in their speed of operation due to lack of dies capable of permitting 20 the drawing of wire therethrough at high speeds. These machines are now operating at speeds as high as wire can be commercially drawn through the dies used therein. After a long series of tests with dies of 25 the types heretofore used and also with various different designs of dies made up during the course of my investigation, I have discovered that the relation between the length and the diameter of the wire 30 reducing opening and also the contour thereof at the entrance end materially influence the pull required to draw the wire through the die, the accuracy of the size of the drawn wire, the speed at which wire 35 may be drawn through the die without breakage, and the length of time which the die can be used for a given size of wire. For example, there is a definite relation 40 between the length of the wire reducing portion of the die and its diameter which will provide the greatest resistance to wear on the die and at the same time will provide for the minimum resistance to the pull of the wire through the die, while insuring 45 that the wire will undergo a complete physical change from the larger to the desired reduced size. Also, it has been found that if the wire reducing opening is connected with the mouth of the die by means of a 50 curved portion which bears a certain relation to the diameter of the wire reducing opening, the amount of pull required to draw the wire through the die will be reduced to a minimum, thereby eliminating 55 the tendency of the wire to break and re-

ducing the amount of friction between the die and the wire.

The dimensions which have been determined as best adapted for the structure of the die are those in which the length of 60 the reducing portion is approximately equal to its diameter, while the contour thereof at the entrance to the wire reducing portion is rounded on a radius approximately 65 equal to twice the diameter of the smallest portion of the wire reducing opening. Dies having this construction are capable of drawing number 19 to 40 inclusive B. & S. wire gauge copper wire commercially at approximately 2500 feet per minute without 70 breakage of the wire, whereas with former dies for drawing these sizes of wire the machines have been operated at a maximum speed of reduction of 1600 feet per minute. 75

Dies made either from chilled iron or from diamonds having the proportions above described are capable of high speed reductions for a length of time that is commercially satisfactory.

In the drawings illustrating this invention:—

Fig. 1 is a vertical sectional view of a die illustrating this invention;

Fig. 2 is the same as Fig. 1 with the wire inserted;

Fig. 3 is a view illustrating a form taken by the wire as it is drawn through the die, and

Fig. 4 is a fragmentary plan view of the die.

As shown in the drawings, 5 designates a die body which may be supported by a suitable supporting member 6 fragmentarily shown. At one end of this die there is provided a mouth or tapered opening 7 which is larger at its upper end than the diameter of a wire 8 to be reduced and is tapered inwardly toward a straight sided reducing portion 9 which has the diameter of the drawn wire 10. The length L of the 100 narrowed or reducing portion of the opening 9 should be approximately equal to the diameter or d' of this opening in order that the wire will undergo such physical changes that it will become completely set 105 in its reduced size before emerging from the die and the die will not be subjected to too great wear. Also this length is not so great as to introduce extra friction to the drawing of the wire.

Connecting the mouth or tapered portion 7 with the narrow or reducing portion 9 is a curved portion 12 which is tangential to both the mouth and reducing portion 7 and 9, and the radius of curvature R of this curved portion is approximately equal to twice the diameter d' of the straight sided reducing portion 9. This curvature has been found to offer the least resistance 10 to the drawing of the wire. At its lower end the straight sided or reducing portion 9 is slightly beveled or rounded, as shown at 13, to prevent cutting or abrading of the wire in case it becomes necessary to 15 back up the wire in the die for any reason.

What is claimed is:

1. A wire drawing die having a reducing portion in which there is a straight por-

tion having approximately the same length as diameter.

2. A wire drawing die having a straight reducing portion the entrance into which when viewed in cross-section is rounded on a radius approximately equal to twice the diameter of the straight reducing portion. 25

3. A wire drawing die having a wire reducing opening in which there is a straight portion having approximately the same length as diameter and in which the entrance end, when viewed in cross section, 30 is rounded on a radius approximately equal to twice the diameter of the straight portion.

In witness whereof, I hereunto subscribe my name this 28th day of April A. D., 1920.

HARRY BLOUNT.
